CARL S. MORTENSON, OF MOLINE, ILLINOIS.

SAW-CLAMP.

1,089,429.

Specification of Letters Patent. Patented Mar. 10, 1914.

Application filed May 10, 1913. Serial No. 766,694.

To all whom it may concern:

Be it known that I, CARL S. MORTENSON, a subject of the King of Sweden, residing at Moline, county of Rock Island, and State of Illinois, have invented certain new and useful Improvements in Saw-Clamps, of which the following is a specification.

This invention relates to saw clamps and is particularly adapted for use when holding 10 a saw to be sharpened or repaired.

The primary object of my invention is to provide a clamp of such character that a saw may be rigidly secured to a work bench or table with the least possible danger of injury 15 to the saw, or that the saw will become loose in the clamp.

A further object of my invention is to provide a saw clamp of such construction that it may be easily and quickly attached 20 to a work bench or other support, and in which a saw may be quickly and rigidly secured; the simplicity of the attaching and clamping part, and their novel arrangement being such that the chances of breakage or 25 derangement of the several parts is reduced to a minimum.

A still further object of my invention is to provide a saw clamp of such construction that when not in use it may be folded 30 or collapsed in such manner as to require but a small amount of room in storage.

With these objects in view my invention consists in a pair of parallelly disposed clamping members, one of which is secured 35 at each end to bench clamps, and means for moving the other of the said clamping members into or out of clamping engagement with the first named member.

My invention further consists in a pair 40 of parallelly disposed clamping members as above characterized, one of which is permanently secured at each end to bench clamps, yokes adjacent the said end and pivotally connected at one end thereto, the other of 45 said clamping members being connected to the other end of said yokes and coöperating means upon said clamping member and yokes for forcing said movable clamping member into engagement with the permanently secured member when the said yokes 50 are turned on their pivots.

My invention further consists in various 55 details of construction and arrangements of parts all as will be fully described herein-after and particularly pointed out in the claims.

My invention will be better understood by reference to the accompanying drawings in which—

Figure 1 is a view taken through a work 60 bench and showing in elevation a clamp constructed in accordance with my invention, Fig. 2 is a top plan view of the same, Fig. 3 is a sectional view taken substantially upon the line α — α of Fig. 2, and showing the same 65 upon an enlarged scale, Fig. 4 is an elevation of the saw clamp illustrating the manner in which it is folded when not in use, Fig. 5 is an enlarged elevation of one end of the movable clamping member, and Fig. 6 is 70 a similar view of one end of the yoke member.

Referring now more particularly to the drawing 1 and 2 indicate a pair of saw engaging jaws, arranged in parallel relation 75 and provided with smooth faces on their adjacent sides to engage the saw. These jaws are connected and held in their different positions relatively to each other by a pair of yokes 3, one arranged adjacent each end. 80 One end 4 of each yoke is pivoted to the inner saw engaging jaw 2, while the opposite end extends across and supports the opposite saw engaging jaw 1. This latter jaw is secured to the yoke member by a pin or bolt 85 8 which is rigidly secured to the said jaw member 1, and which extends through an opening 5 in said yoke end. The adjacent faces of the yoke end and the jaw member 1 are provided with cam faces, that is, the 90 yoke member 3 is provided with a cam lug 6 which rides upon the adjacent face of the jaw member 1, and is adapted normally to fit into the cam depression 7 in the latter said face. The pin or bolt 8 which forms 95 this pivotal connection, is extended beyond the yoke member and is provided with a head 9. A coil spring 10 is interposed between the bolt head 9 and the yoke to normally force the jaw member 1 into frictional engagement with the inner face of the yoke. It will be seen from this construction that when the yoke member is in vertical position, the lug 6 upon the inner face thereof will 100 rest in the cam depression 7 upon the adjacent face of the saw clamping jaw 1, and when in this position the pressure of the coil spring 10 upon the bolt 8 forces the said jaw member outwardly, and away from its coöperating jaw member. When it is desired to place a saw within the jaws, the saw 110 is inserted between the jaw faces when in

this position, and then the yoke members are turned slightly until the cam lug 6 rides up out of the depression upon the jaw member 1 and forces the said jaw member toward 5 the coöperating jaw member 2 and thus firmly grips the saw between the two faces.

For the purpose of securing the device thus assembled upon a work bench or table, I resort to the use of a clamp shown in the 10 several figures, and which is fully illustrated in Fig. 3 of the drawings. This clamp comprises vertical members 11, each of which is provided with a pair of rearwardly extending arms 12 and 13, spaced apart a distance 15 sufficient to admit of the device being positioned over the edge of the bench or table, and the lower arm 13 is provided with a thumb screw 14 for holding the same securely in position. The upper end 15 of the 20 vertical member of the clamp is secured to the saw clamp through the medium of the bolt 16, which bolt secures together in pivotal relation, the end 4 of the yoke, and also the saw clamping jaw 2. It should be noted 25 that the member 11 is straight and is secured between the outer face of the jaw 2 and the adjacent yoke end, so that it may fold against said outer face as shown in Fig. 4.

From the construction of the yoke members, and the clamps for attaching the device to the bench or table, it will be readily understood that when the device is not in use it may be quickly and easily detached from its position upon the table, and the securing 35 clamps folded inwardly to lie in the same plane with the saw clamping jaws, and the yokes also turned inwardly, thereby forming a neat and compact structure which will occupy but little room.

40 Having described my invention, I claim:

1. In a device of the class described, a fixed and a movable jaw, pivotally mounted means connecting said jaws and adapted to move the same into and out of engagement 45 with each other, and means for securing the device to a bench, said means being pivotally mounted upon the outer face of the fixed jaw and adapted to fold against said face, substantially as described.

50 2. A saw clamp comprising a pair of parallelly disposed jaw members, yokes adjacent each end of the said jaw members and having their ends pivotally connected to said jaws respectively, and coöperating cam faces 55 upon the adjacent faces of the said yoke and the said last named jaw member whereby the said jaw will be forced into engagement with the first named jaw member when the yokes are turned on their pivots, substantially as described.

60 3. A saw clamp comprising a pair of parallelly disposed jaw members, yokes adjacent each end of the said jaw members and having their ends pivotally connected to said 65 jaws respectively, coöperating cam faces

upon the adjacent faces of the said yoke and the said last named jaw member, whereby the said jaw will be forced into engagement with the first named jaw member when the yokes are turned on their pivots, and means 70 secured to one of said jaws for attaching the device to a bench, substantially as described.

4. A saw clamp comprising a pair of parallelly disposed jaw members, yokes adjacent each end of the said jaw members and having their ends pivotally connected to said jaws respectively, and coöperating cam faces upon the adjacent faces of the said yoke and the said last named jaw member whereby the said jaw will be forced into or out of 75 engagement with the first named jaw member when the yokes are turned on their pivots, substantially as described.

5. A saw clamp comprising a stationary jaw, a movable jaw, a yoke pivotally mounted at each end of the first named jaw and embracing the movable jaw, coöperating cam faces upon the movable jaw and the adjacent ends of the yoke adapted to force said movable jaw into engagement with the 80 first named jaw, and means whereby the movable jaw is held to frictionally engage the coöperating faces of the yoke member, substantially as described.

6. A saw clamp comprising fixed and 95 movable parallelly disposed jaws, yokes adjacent each end of said jaws and having their opposite ends pivotally connected to said jaws respectively, coöperating means upon the adjacent faces of the said movable 100 jaw and the said yoke end whereby said jaw is moved into or out of engagement with the said opposite jaw when said yoke is turned on its pivot, and means for retracting said movable jaw and yieldingly holding the 105 same into engagement with its coöperating yoke end, substantially as described.

7. A saw clamp comprising fixed and movable parallelly disposed jaws, yokes adjacent each end of said jaws and having 110 their opposite ends pivotally connected to said jaws respectively, coöperating cam faces upon the adjacent faces of the said movable jaws and said yoke end whereby said jaw is moved into or out of engagement with the said opposite jaw when said yoke is turned on its pivot, and means for retracting said movable jaw and yieldingly holding the 115 same into engagement with its coöperating yoke end, substantially as described.

8. A saw clamp comprising fixed and movable parallelly disposed jaws, yokes adjacent each end of said jaws and having their opposite ends pivotally connected to said jaws respectively, coöperating means 125 upon the adjacent faces of the said movable jaw and said yoke end whereby said jaw is moved into or out of engagement with the said opposite jaw when said yoke is turned on its pivot, means for retracting said mov- 130

able jaw and yieldingly holding the same into engagement with its coöperating yoke end, and attaching clamps pivoted to said fixed jaw to fold upon the same, substantially as described.

9. In a device of the class described a fixed and a movable jaw, a pair of yokes each having their ends pivotally connected to said jaw respectively, coöperating means on said movable jaw and the adjacent yoke ends for moving the last said jaw into and out of engagement with the fixed jaw, mem-

bers pivotally connected to said fixed jaw between the outer face thereof and the adjacent yoke ends, and means on said members for attaching the device to a bench, substantially as described. 15

In testimony whereof I have signed my name to this specification in the presence of two subscribing witnesses.

CARL S. MORTENSON.
